UNITED STATES PATENT OFFICE.

WILLIAM HAZLETON, OF DELAWARE, OHIO.

DOUBLE-CEMENT-BLOCK MACHINE.

1,196,684.

Specification of Letters Patent. Patented Aug. 29, 1916.

Application filed April 3, 1915. Serial No. 19,010.

To all whom it may concern:

Be it known that I, WILLIAM HAZLETON, a citizen of the United States of America, residing at Delaware, in the county of Delaware and State of Ohio, have invented certain new and useful Improvements in Double-Cement-Block Machines, of which the following is a specification, reference being had therein to the accompanying drawing.

10 This invention relates to a double cement block machine and has for its object the production of a simple and efficient means for shifting the molds of the cement block from under the tamper so as to facilitate 15 the removal of the blocks from the mold boxes.

Another object of this invention is the production of a simple and efficient means for holding the mold boxes in a removable 20 position, and also facilitating the release of the several parts of the box to permit the contents of the box to be readily discharged therefrom.

With these and other objects in view this 25 invention consists of certain novel combinations, constructions, and arrangements of parts as will be hereinafter fully described and claimed.

In the accompanying drawings:—Figure 30 1 is a side elevation of the cement block machine. Fig. 2 is a section taken on line 2—2, of Fig. 1. Fig. 3 is a top plan view of the cement block machine. Fig. 4 is a central longitudinal section through the machine. 35 Fig. 5 is a side elevation of the block molds taken upon the opposite side from that shown in Fig. 1. Fig. 6 is a section taken on line 6—6, of Fig. 1. Fig. 7 is a section taken on line 7—7, of Fig. 1. Fig. 8 is a detail 40 perspective of one of the mold boxes. Fig. 9 is a detail perspective of one end of the frame of the device. Fig. 10 is a detail perspective of the bracket which is adapted to carry the connecting pulley for the cement 45 boxes or molds. Fig. 11 is a section taken on line X—X, of Fig. 3. Fig. 12 is a detail perspective of one of the latch bars. Fig. 13 is an end view of one of the latch bars showing the manner in which the latch bar engages 50 one of the locking arms, the locking arm being shown in section. Fig. 14 is a vertical section through the toggle machine for actuating the latch bars. Fig. 15 is a detail perspective of the stop bracket used in connection 55 with the present invention.

By referring to the drawings it will be

seen that 1 designates the frame which is supported upon a plurality of legs or standards 2 placed at each end thereof, and an auxiliary frame 3 is carried intermediate the frame 1 and comprises a plurality of standards or legs 4. The frame 1 comprises a plurality of longitudinally extending rails having a track 5 which has an upper convex face upon which fits the concave track 6, 60 which track is carried by the respective mold boxes 7 hereinafter described. The auxiliary frame 3 carries a drum 7' and this drum is supported upon a shaft 8, and to this shaft 8 is secured a crank wheel 9 for facilitating 65 the rotation of this drum 7'. A pulley sheave 10 is secured at each end of the frame 1 as clearly illustrated in Fig. 4 of the drawings, and a pulley 11 is mounted within each sheave over which pulley are adapted to pass 70 the cables 12. It should be understood that two of these cables are employed one cable extending opposite to the other as illustrated in Fig. 4 and being secured to opposite sides of the drum 7 as illustrated clearly in Fig. 4 75 of the drawings. The cables 12 extend around the respective pulleys 11 as above described and also extend around the pulleys 13 carried by the pulley sheaves 14 secured to the bottom of the mold boxes 7. The opposite ends of the cables 11 are then fixedly 80 secured to the respective ends of the frame 1 as indicated clearly in Figs. 3 and 4 of the drawings.

As stated above a pair of these mold boxes 90 7 are employed, and these boxes are held in spaced relation by means of a spacing or coupling band 15 which is detachably secured to the respective boxes 7 by means of bolts 16 illustrated in Fig. 4. It will, therefore, be seen that it is only necessary to have the pulley sheaves connected to one end of the boxes 7, although, of course, it should be understood that these sheaves may be placed at each end of the box where only one box is 95 desired, as the same may be used with one box in place of two boxes as will be clearly understood and without departing from the spirit of the invention.

It, of course, should be understood that 100 the boxes 7 are adapted to be placed under a tamper for the purpose of packing the cement within the mold, and when it is desired to remove the boxes, the tamper is released and the boxes moved toward the opposite end of the frame to that shown in Fig. 1. 110 Each box 7 is provided with a hinged front

plate 17 clearly illustrated in detail in Fig. 8, and this hinged front plate 17 is securely hinged to the base of the box 7 by means of a pintle 18. The box 7 is also provided with a pair of hinged end partitions 19 which are securely hinged to the box 7 by means of pintles 20. These end partitions 19 are provided with a plurality of spaced arms 21, which spaced arms project beyond the ends of the respective end partitions 19.

As clearly illustrated in Figs. 1 and 8 of the drawings it will be seen that the front plate 17 carries a pair of parallel longitudinally extending latch bars 24, which latch bars are provided with a plurality of spaced notches 25 formed in their respective ends thereof for the purpose of fitting against or over the inner edges of the arms 21. These latch bars 24 are connected together by means of the toggle members 26, one of the toggle members being provided with a stop lug 27 of the usual construction for limiting the toggle members 26 in one direction. An operating handle 28 is pivotally secured to the front plate 17 and is connected to the pivot pin 29 of the toggle members 26 by means of a link 30. It will, therefore, be seen that when it is desired to draw the latch bars 24 out of engagement with the inner faces of the arms 21, the lever 28 is swung in one direction for releasing the latch bars, but when the latch bars are desired to be locked into engagement with the arms 21 it should be understood that the operating lever or handle 28 is swung in the opposite direction. By carefully considering Fig. 8 it will be seen that the upper arm 21 of each end partition is provided with a projecting hand-hold 31 for facilitating the handling of the box and also the setting of the same in the desired position.

It should be further understood that the latch bars 24 by having a plurality of notches 25 at each end thereof will permit the end partitions 19 to be adjusted to the position shown in dotted lines in Fig. 3 to permit the formation of a block having ends tapering toward one side thereof such as for instance for the purpose of forming a silo block, which construction is, of course, necessary in order to produce a circular formation of a silo. It should be understood that the rear plates 32 of the boxes 7 are reinforced by means of the vertically extending staves 33 which are connected to the strap members 34, which strap members are hingedly secured to the pintle members 20 above described.

It should be understood that the frame 1 carries a stop bracket 35 at each end thereof which is secured to the frame 1 by means of a bolt 36. This stop bracket 35 is provided with an adjustable bolt 37 for the purpose of regulating the stop of the boxes 7 as the same are moved longitudinally of the

frame 1. It should be understood that one of these brackets 35 is positioned at each end of the frame 1.

A door supporting bracket 38 is supported near one end of the frame 1 upon one of the legs 2 and also upon one of the legs 4 of the auxiliary frame 3, these brackets being so placed as to be direct in front of the boxes 7 when the same are moved toward one end of the frame 1. Each bracket 38 is provided with an upwardly extending lip 39 for limiting the forward movement of the front panel 17 as the same is moved downwardly or thrown downwardly to this position. This lip or tongue 39 will prevent the forward movement of the box 7 as the cement block which has been formed therein is being removed therefrom. As stated above and as clearly illustrated in Fig. 1, these brackets 38 are positioned correctly so as to receive the front panels 17 as the same are swung downwardly for the purpose of releasing a cement block therefrom.

Having thus described the invention what is claimed as new, is:—

1. In a machine of the class described, the combination of a frame, tracks fixedly mounted upon said frame, said tracks having convex upper faces, mold boxes positioned upon said frame, longitudinally extending tracks fixedly mounted upon the lower portions of said boxes, said last-mentioned tracks having concaved lower faces, said last-mentioned tracks fitting throughout their entire length upon said first mentioned tracks, whereby said boxes will be supported throughout their entire length and thus be positively prevented from sagging, and means for drawing said boxes across said frame.

2. In a machine of the class described, the combination of a frame, tracks fixedly mounted upon said frame, said tracks having convex upper faces, mold boxes positioned upon said frame, longitudinally extending tracks fixedly mounted upon the lower portions of said boxes, said last-mentioned tracks having concaved lower faces, said last-mentioned tracks fitting throughout their entire length upon said first-mentioned tracks, whereby said boxes will be supported throughout their entire length and thus be positively prevented from sagging, means for limiting the longitudinal movement of said boxes upon said frame, and means for drawing said boxes across said frame.

3. In a machine of the class described, the combination of a frame, tracks fixedly mounted upon said frame, said tracks having convex upper faces, mold boxes positioned upon said frame, longitudinally extending tracks fixedly mounted upon the lower portions of said boxes, said last-mentioned tracks having concaved lower faces,

5 said last-mentioned tracks fitting throughout their entire length upon said first-mentioned tracks, whereby said boxes will be supported throughout their entire length
10 and thus be positively prevented from sagging, vertical brackets fixedly mounted upon said frame adjacent its end, an adjustable bolt carried by each bracket, whereby the movement of said boxes along said frame will be limited, and means for drawing said boxes across said frame.

15 4. In a machine of the class described, the combination of a frame, mold boxes slidably mounted upon said frame, said boxes having drop front partitions, means for removably holding said front partitions in set-up positions, and means carried by said frame for supporting said drop partitions as the same are swung downwardly for facilitating
20 the removal of plastic blocks from said boxes.

5. In a machine of the class described,

the combination of a frame, mold boxes 25 slidably mounted upon said frame, said boxes having drop front partitions, means for removably holding said front partitions in set-up positions, a horizontal bracket carried by and extending from the side of said frame, said bracket having an upwardly extending lip at its outer end, said bracket being 30 adapted to support said panels when the same are swung downwardly for facilitating the removal of plastic blocks from said boxes, and said lip being adapted to engage the outer edges of said panels when in a 35 lowered position, whereby said boxes will be held against side movement upon said frame.

In testimony whereof I hereunto affix my signature in presence of two witnesses.

WILLIAM HAZLETON.
